(74) Attorney, Agent, or Firm—Price, Heneveld, Cooper,
DeWitt & Litton LLP**CLAIM**

We claim the ornamental design for a control for seating unit, as shown and described.

DESCRIPTIONFIG. 1 is a front perspective view of a control for seating unit embodying the present invention; and,
FIGS. 2–6 are fragmentary right side, front, rear, top, and bottom views, respectively, of the control for seating unit shown in FIG. 1.

The dashed lines in FIGS. 1–6 show the environment of the present articles, but do not form a part of the claimed invention.
